United States Patent

Des. 235,309

235,309

AEROSOL CONTAINER

**Carol Schafer, 1627 Pontius,
Los Angeles, Calif. 90005**

Filed Dec. 22, 1969, Ser. No. 20,586

Term of patent 14 years

Int. Cl. D9—01

U.S. CL. D9—8

FIG. 12

FIG. 13

FIG. 14

FIG. 1 is a perspective view of an aerosol container showing my new design;

FIG. 2 is a front elevational view;

FIG. 3 is a top plan view; and

FIG. 4 is an elevational view looking from the left of FIG. 2.

I claim:

The ornamental design for an aerosol container, as shown.
